CARDIOMETER FOR MONITORING HEARTBEATS

Bernard B. King, Venice, Calif., assignor, by mesne assignments, to Douglas Aircraft Company, Inc., Santa Monica, Calif., a corporation of Delaware

Filed June 23, 1966, Ser. No. 2,794

Term of patent 14 years

(Cl. D83—1)

FIGURE 1 is a perspective view taken from the top and left side of a cardiometer for monitoring heartbeats embodying my new design;

FIGURE 2 is a top plan view thereof;

FIGURE 3 is a side elevational view taken from the right side thereof;

FIGURE 4 is a rear elevational view thereof; and

FIGURE 5 is a front elevational view thereof.

The bottom plan view, not shown, of the cardiometer, is substantially plain.

The dominant features of my design reside in the portions shown in full lines.

The broken line representation of the pickup head illustrated in FIGURE 1 has been omitted in FIGURES 2 to 5 inclusive for ease of illustration.

I claim:

The ornamental design for a cardiometer for monitoring heartbeats, substantially as shown and described.
